Patented Jan. 30, 1923.

UNITED STATES PATENT OFFICE.

LAURENCE G. HANMER, OF NEW YORK, N. Y.

RADIATOR.

Application filed April 19, 1920. Serial No. 374,860.

To all whom it may concern:

Be it known that I, LAURENCE G. HANMER, citizen of the United States, and a resident of New York city, in the county of New York and State of New York, have invented 5 certain new and useful Improvements in Radiators, of which the following is a specification.

My invention relates to improvements in 10 radiators and more particularly to cellular or tubular radiators such as are commonly used in automobiles and other motor vehicles. The main object of the invention is to provide a cellular or tubular radiator in 15 which visible portions of some of the cooling elements or parts thereof are formed differently from others or some of the cells deformed with respect to others to produce a 20 definite predetermined design in the radiator tors such as for example, a monogram or trade mark. Further and more specific objects, features and advantages will more clearly appear from the detail description given below taken in connection with the accompanying sheet of drawings which form a 25 part of this specification.

Referring to the drawings Fig. 1 is a front view of a radiator embodying my improvements in a preferred form thereof. Fig. 2 is 30 a rear view of the same radiator. Fig. 3 is a transverse section of a portion of the radiator illustrated in perspective.

Referring to the drawings, 3 represents a 35 radiator frame of any well-known or suitable variety holding in place and cooperating with the built-up cells 4. The radiator shown is of well-known variety adapted for the cooling of water which may be introduced at the top end of the frame 3 and 40 passes down between the cells 4 through which cells cooling air is adapted to pass to cool the water.

In the preferred and particular embodiment of the invention shown, the cells 4 are 45 made up of sheets of brass. For example, one sheet 5 is stamped to form an off-set at 6 along one edge and another off-set at 7 along the opposite edge, and is bent to form a transverse wall at 8. Opposing the sheet 5 50 is a similar sheet 9 having corresponding opposing off-sets at 6 and 7 and bent to form transverse walls 9 substantially evenly spaced between the walls 8 of the sheet 5. In this way a row of cells is constructed, the 55 side walls of which are composed of the sheets 5 and 9 and the transverse partition

walls of which are formed by the portions 8 and 9. This row of cells I have indicated by the letter A. Another row of cells lying adjacent thereto and constructed in the same 60 manner I have indicated by B. Also I have indicated a third row of cells, similarly constructed and placed adjacent the row B, by the letter C. D represents a similar row of cells except that they are reversed end for 65 end so that the off-sets at 6 are at the opposite side of the radiator from the off-sets 6 in rows A, B and C. E represents a row of cells arranged and constructed like the row D and placed adjacent thereto. F represents 70 a similar row of cells similarly constructed and arranged and placed adjacent the row E. In order that the various rows of cells may be firmly secured together the ends thereof forming the faces of cellular portion 75 of the radiator are dipped in solder so that the various layers are secured firmly together. That is, in the rows A, B and C for example, the off-sets 7 of one row are firmly soldered to the off-sets 7 of the next row 80 and the off-sets 6 of one row are firmly soldered to the off-sets 6 of another row. And in the cells D, E and F the off-sets 6 of one row is firmly soldered to the off-sets 6 of another row and the off-sets 7 in one row are 85 firmly soldered to the off-sets 7 of another row. As to the two rows C and D it is noted, however, that the off-set 7 on one side of cells C is firmly soldered to off-set 6 on one side 90 of cells D, and the off-set 6 on one side of cells C is firmly soldered to the off-set 7 on one side of cell D. By reason of the position which the off-sets 6 and 7 occupy on the brass sheets, it will be seen that at one end 95 there are formed between the rows of cells A, B and C relatively wide grooves 10 and 11 which become filled with solder and at the other end similar wide grooves 12 and 13 are formed between the cells D, E and F which also become filled with solder and between the cells C and D grooves 14 are 100 formed of medium width which likewise become filled with solder while no such grooves are formed between the off-sets 6 at 15 and 16. Water passages between the various 105 rows of cells are indicated at 17. Thus on one face of the radiator the ends of some of the cells become deformed with respect to others since the walls at the ends of some of the cells are thicker than others and this is 110 accomplished in the particular arrangement shown by the reversing of some of the cells

as indicated in Fig. 3. Referring to Fig. 1 wherein by this means the monogram or initials F B A are formed in the radiator, the vertical heavy black lines of these letters are 5 formed by the relatively wide ends of the walls of the cells which are made to appear relatively wide by reason of the distortion of the sheet metal whereby the grooves 10 and 11 are formed which are filled with solder. 10 The relatively thin vertical lines in Fig. 1 indicate the walls of the cells around the letters F B A and form a field therefor. These end walls are indicated by the end walls 15 in Fig. 3. That is, the front of the radiator 15 as shown in Fig. 1 has the ends of the walls of the cells relatively thin except those portions indicated by the letters F B A which are made relatively thick by the reversing of the cell forms at such portions. This reversal of cell forms will also produce corresponding deformations at the rear of the radiator as illustrated in Fig. 2 except that the field or the larger part of the rear face of the radiator will have the vertical walls in 25 view, relatively thick while the vertical walls in the letters F B A will be relatively thin as indicated at 16 in Fig. 3 and the letters F B A will read backwards.

In this way it will be seen that by properly reversing the cells or blocks of cells, constructed along the lines indicated, any 30 definite predetermined design may be formed in the face of the radiator which will have the appearance of a mosaic. Designs 35 may be thus worked in radiators which will permit the motor vehicle to be easily recognized in case it is stolen. It is not necessary that the design be also worked in the rear of the radiator although by the particular arrangement shown this comes about 40 automatically and makes it all the more difficult for the design to be effaced. It will also be understood that such a definite predetermined design may be put in such a 45 radiator by deforming visible portions of the cooling elements in many other ways and if desired, such deformation may extend through the body of the radiator from one side to the other. On the other hand the 50 deformation may be produced by merely bending the end of part of the cooling elements to deform them in any other way than that shown in Fig. 3. Also the walls may be made thicker or deformed merely 55 by the application of solder or other metal in other ways, the main idea being the giving of a different appearance to some of the cells or cooling elements by reason of variations in thickness of metal or apparent thickness 60 of metal or by deforming the metal in any way so as to produce a definite predetermined design in radiators. Thus while I have described my improvements in great detail and with respect to one preferred form thereof, I do not desire to be limited 65

to such details and form since many changes and modifications may be made and the invention embodied in widely different forms without departing from the spirit and scope thereof in its broader aspects.

70

What I claim as new and desire to secure by Letters Patent, is:

1. A radiator having cooling elements providing liquid passages and cooling passages the ends of some of the cooling elements differently fashioned with respect to others and the differently fashioned elements being grouped to produce a definite predetermined design in one section of the radiator, surrounded by a substantially uniform background, substantially as described.

75

2. A radiator having a plurality of cooling elements providing liquid passages, the visible portion of some of said elements or parts thereof being formed differently from the visible portion of adjacent cooling elements or parts thereof to produce a definite predetermined design in the radiator.

80

3. A cellular radiator of the class described having cells providing liquid passages the walls at the ends of some of the cells thicker than others to produce a definite predetermined design in the radiator.

85

4. A cellular radiator having cells providing liquid passages the walls at the front ends of some of the cells thicker than others to produce a definite predetermined design in the front of the radiator and the walls at the rear ends of some of the cells different in thickness from those of others, to produce substantially the same design in the rear of the radiator.

90

5. A cellular radiator having a plurality of cellular structures providing liquid passages, the cellular structures being substantially alike except for the visible portions of the ends of the cells, the visible portions of some of the cells being formed differently from the visible portions of adjacent cells to produce a definite predetermined design in the radiator.

105

6. A cellular radiator having cells providing liquid passages, the visible portion of some of its cells formed differently from the visible portions of adjacent cells, the cells being grouped to produce a definite predetermined design in part of one face of the radiator with a background for the design of different arrangement.

110

7. A radiator having a plurality of like cooling elements providing liquid passages, the ends of some of said like cooling elements being differently fashioned with respect to others to produce a definite predetermined design in one section of the radiator.

115

Signed at New York, in the county of New York, and State of New York, this 15th day of April, A. D. 1920.

LAURENCE G. HANMER.
